UNITED STATES PATENT OFFICE

MARCEL JANNIN, OF MEUDON, FRANCE

INTERNAL COMBUSTION ENGINE

Application filed October 30, 1930, Serial No. 492,160, and in France November 5, 1929.

The present invention relates to internal combustion engines of the so called "barrel" type wherein the pistons reciprocate in substantially parallel relation to the crankshaft.

5 One of the objects of the invention is to eliminate the losses of power due to end-thrust.

Another object is to provide a special end-to-end assembly of two motors eliminating 10 end-thrust losses and yielding more perfectly balanced effects.

An additional object is to provide an improved universal connection between the pistons and the elements driven thereby.

15 Further objects will appear in the course of the detailed description now to be given with reference to the accompanying drawings, in which:—

Fig. 1 is an axial section through one illustrative embodiment of the invention;

Fig. 2 represents the same motor in sectional perspective;

Fig. 3 illustrates the transmission of the various forces and couples from the pistons 25 to the crank-shaft;

Fig. 4 shows, in section, a special end-to-end motor assembly.

Referring to Fig. 1 of the drawings, there is shown a seven cylinder, 4-cycle, air-cooled, 30 engine consisting of the following elements: a crank-shaft 1 of the Z-type and including an inclined portion 11; a pair of fixed casings 2 and 3 supporting the crank-shaft and piston assemblies; a plurality of cylinders 4 supported on casing 3 and provided with cooling fins 5; a plurality of pistons 6 mounted to reciprocate in cylinders 4 and terminating in spherical recesses at one end; a pair of spaced spherical segments 8 in frictional 35 contact with said spherical recesses; a flange 7 fitting between segments 8 and integral with a frusto-conical shell 9 terminating in a bearing surface 10 which fits over inclined portion 11 of crank-shaft 1; a universal assembly 40 designed to prevent rotation and axial displacement of shell 9 and including a ring 12, four pins 13 rigidly connected to ring 12 and having their axes aligned in pairs lying at right angles, two bearings 27 (Fig. 50 2) integral with shell 9 and two bearings

14 integral with casing 3, bearings 14 being positioned so that the corresponding axis of pins 13 supported therein pass through point 15 where the axis of the horizontal and inclined portion 11 of crank-shaft 1 intersect; 55 a spark-plug 16 mounted in the head of a combustion chamber fitted with intake and exhaust valves 17 and 18; a drum 19 provided with cam surfaces 20 and 21 controlling valves 17 and 18; a speed reducing train 22, 23, 24, 25 driven from the crank-shaft; and a counter-weight 26 attached to the latter.

The hereinabove described assembly functions as follows: assuming that a rotary movement be imparted by an external source 65 to crank-shaft 1, inclined portion 11 will move bearing 10 through a circular path; but, since shell 9 is prevented from turning by universal assembly 12, 13, 14, said shell will oscillate about point 15 and points along 70 the circumference of flange 7 will describe reciprocating movements which will be transmitted to pistons 6. However, if pistons 6 be reciprocated in properly timed relation, their movement will be transformed, by an 75 inverse mechanism, into a rotary movement of crank-shaft 1. The timing of successive explosions may be effected by assembly 19, 20, 21 in a manner which will at once be evident to those skilled in the art. 80

The detailed mechanism of transmission of power from the pistons to the crank-shaft is shown in Fig. 3. Pistons 6 are forced to the left under pressure P of the gases in the combustion chamber and react on flange 7 in 85 a direction normal thereto F_1 , the pistons reacting on the cylinders in direction f . Flange 7 thereupon tends to move to the left and turn about point 15 in a counter-clockwise direction. Ring 12 will act to prevent displacement of the flange to the left, thus submitting casing 3 to the action of forces F_2 and F_3 which will balance the pressure F_4 exerted by the explosion on the cylinder head. The tendency of flange 7 to rotate about point 15 will, at the same time, give rise to a thrust F_5 exerted by bearing 10 on inclined portion 11 of the crank-shaft and tend to rotate the latter. It is to be noted that the thrust exerted by bearing 10 is 95 100

radial (i. e. there is not axial component along 11) and no abutment or thrust element need be used in combination with bearing 10.

In the form of assembly shown in Fig. 4, 5 two motors of the type shown in Figs. 1 to 3 are mounted end-to-end to obtain perfect balance and eliminate waste of power due to end thrust. This motor is of the two-cycle, 10 water-cooled type and consists of the following structures: a plurality of cylinders 28 positioned around the crank-shaft and supported in a block 29 provided with a water-jacket 30; an intake conduit 31; an exhaust conduit 32; openings 33 for the fuel injectors, 15 a double-Z crank-shaft 34 supported on block 29 by a central bearing 35 and including oppositely inclined portions 38 and 39; end-casings 36 supporting the ends of the crank-shaft; pairs of bearings 40 corresponding to 20 elements 10 (Fig. 1) and integral with corresponding conical shells; flanges or inclined plates 48 rigidly attached to the conical shells; rings 41, similar to elements 12, universally mounted between bearings 43 forming part 25 of block 29 and bearings (not shown) corresponding to split-bearings 27 (Fig. 2) integral with the conical shells, the inner pairs of the latter being provided with recesses 42, to 30 permit movement of said shells relative to bearings 43; and spherical segments 44 serving to support inclined plates 48 and fitting into corresponding recesses formed in the ends of opposed pairs of pistons 45.

Pistons 45 are mounted so that at the extremity of their course they uncover ports 32 and 31 communicating with the exhaust and intake manifolds respectively.

This form of apparatus functions exactly as does the one shown in Figs. 1 to 3, the reciprocating movement of the pistons causing plates 48 to oscillate about points 49 and 50. When the pistons reach the end of their course, ports 46 will be discovered and the 45 burnt gases will be driven thereinto by the air entering under low pressure through ports 47. The scavenging air may be furnished by a compressor driven by the motor itself or by an auxiliary source of power. This 50 type of motor is not only perfectly balanced but, in view of the mounting of the pistons in opposed pairs inside a single cylinder, the scavenging of burnt gases may be more completely effected.

55 Since, as already indicated, machines of this type are reversible, it is quite obvious that by coupling the crank-shaft to a source of power, compressing, pumping or evacuating effects may be produced by pistons mounted either as shown in Figs. 1 to 3 or as in Fig. 4.

In the claims that follow, the term "shell" is used generically to indicate integral assembly 7, 9, 10 in Fig. 1 and a composite assembly 65 of the type of 40, 40, 48 in Fig. 4.

What I claim is:—

1. In combination, a crank-shaft including a pair of aligned portions coinciding with the axis of rotation thereof and an inclined extending portion positioned between said aligned portions, a fixed casing assembly including a plurality of cylinders mounted to present a transverse section to planes at right angles to the axis of rotation of the crank-shaft, pistons mounted to reciprocate in said cylinders, a shell having a bearing surface positioned to react on the inclined portion of the crank-shaft, said shell universally connected to said casing and including a flanged peripheral portion, and spherically shaped means positioned to coact with said flanged peripheral portion and with one end of said pistons. 70 75 80

2. In combination, a crank-shaft including a plurality of aligned portions lying along the axis of rotation thereof and a pair of inclined portions intercalated between aligned portions, said inclined portions sloping in opposite directions, a fixed casing assembly including a plurality of cylinders positioned to present transverse sections to planes perpendicular to the axis of rotation of the crank-shaft, pairs of opposed pistons mounted to reciprocate in opposite aligned directions, in said cylinders, a pair of shells each having a bearing surface positioned to react on one of the inclined portions of said crank-shaft, said shells being universally connected to said casing, and means connecting said shells with said pistons. 85 90 95 100

3. In combination, a crank-shaft including a pair of aligned portions coinciding with the axis of rotation thereof and an inclined extending portion positioned between said aligned portions, a fixed casing assembly including a plurality of cylinders mounted to present a transverse section to planes at right angles to the axis of rotation of the crank-shaft, pistons mounted to reciprocate in said cylinder, a shell having two bearing surfaces positioned to react respectively on different portions of said inclined portion of the crank-shaft, said shell being universally connected to said casing by arms mounted substantially in line with the effort being transmitted, and means connecting said shell with said pistons. 105 110 115 120

4. In combination, a crank-shaft including a pair of aligned portions lying along the axis of rotation thereof and an inclined extending portion positioned between aligned portions, said inclined portion being symmetrically disposed relatively to the point where its own axis cuts the axis of rotation of the crank-shaft, pistons mounted to reciprocate in said cylinders, a shell having two bearing surfaces positioned to react respectively on each extremities of said inclined portion of the crank-shaft, said shell being universally connected to said casing by arms 125 130

mounted substantially in line with the effort being transmitted, and means connecting said shell with said pistons.

5. In combination, crank-shaft including 5 pairs of aligned portions mounted along the axis of rotation thereof and a pair of oppositely inclined portions positioned between said aligned portions, said inclined portions sloping in opposite directions, a fixed casing 10 including a plurality of cylinders positioned to present transverse sections to planes perpendicular to the axis of rotation of the crank-shaft, said cylinders being positioned to limit a chamber, pairs of opposed pistons mounted 15 to reciprocate in said cylinders, a pair of shells each having a pair of bearing surfaces supported on the inclined portions of said crank-shaft, these of said bearings adjacent to the central portion of said crank-shaft being mounted inside the chamber limited by 20 said cylinders, means connecting said shells universally to said casing, and means connecting said shells to said pistons.
6. In combination, a crank-shaft including 25 pairs of aligned portions mounted along the axis of rotation thereof and a pair of oppositely inclined portions positioned between pairs of said aligned portion, a fixed casing including a plurality of cylinders and a 30 chamber interiorly, said cylinders being positioned to present transverse sections to planes perpendicular to the axis of rotation of the crank-shaft, pairs of opposed pistons mounted to reciprocate in said cylinders, a 35 pair of shells each having a pair of bearing surfaces contacting with the inclined portion of said crank-shaft, these of said bearings adjacent to the central portion of said crank-shaft being mounted inside said chamber, 40 means universally connecting said shells to said chamber and including arms positioned substantially in line with the efforts transmitted, and means connecting said shells to said pistons.

45 In testimony whereof I affix my signature.
MARCEL JANNIN.
